US00D832789S

(12) **United States Design Patent** (10) **Patent No.:** **US D832,789 S**
(45) **Date of Patent:** **** Nov. 6, 2018**

(54) **ELECTRICAL CONNECTOR**

(71) Applicant: **Quantum Corporation**, San Jose, CA (US)

(72) Inventor: **Scott M. Rockwell**, Denver, CO (US)

(73) Assignee: **QUANTUM CORPORATION**, San Jose, CA (US)

(**) Term: **15 Years**

(21) Appl. No.: **29/556,813**

(22) Filed: **Mar. 3, 2016**

(51) LOC (11) Cl. **13-03**

(52) U.S. Cl.

USPC **D13/147**; D13/133

(57) **CLAIM**

The ornamental design for an electrical connector, as shown and described.

DESCRIPTION

FIG. 1 is a perspective view of my design for an electrical connector shown in a retracted position;

FIG. 2 is a front elevation view of the electrical connector illustrated in FIG. 1;

FIG. 3 is a rear elevation view of the electrical connector illustrated in FIG. 1;

FIG. 4 is a right side elevation view of the electrical connector illustrated in FIG. 1;

FIG. 5 is a left side elevation view of the electrical connector illustrated in FIG. 1;

FIG. 6 is a bottom view of the electrical connector illustrated in FIG. 1;

FIG. 7 is a top view of the electrical connector illustrated in FIG. 1; and,

FIG. 8 is a perspective view of the electrical connector illustrated in FIG. 1, shown in an extended position.

1 Claim, 5 Drawing Sheets
